CIRCUIT BREAKER OPERATING MEANS

George A. Matthews, Detroit, Mich., assignor to
 The Detroit Edison Company, Detroit, Mich.,
 a corporation of New York

Application October 22, 1934, Serial No. 749,401

10 Claims. (C.i. 175—375)

This invention relates in general to circuit breaker operating means and is particularly concerned with a novel arrangement of cooperative parts, whereby improved operation may be attained.

10 In outdoor sub-stations and the like utilizing circuit breakers and disconnecting switches as at present constructed and operated, it is necessary to provide line to ground insulation in the apparatus and devices, and steel structures for supporting the disconnecting devices and the connections to the transmission lines. Obviously, an installation of this type requires extensive ground area and on the whole is exceedingly expensive.

15 To the end that a more economical installation may be provided, this invention proposes to provide a unitary switching device having both circuit breaker and disconnecting switch features, and embodying a novel operating mechanism and control arrangement which will enable the device to be mounted on a transmission line pole or tower in contiguous relation to the transmission line. Means are also provided, whereby the device may be raised and lowered to operate the disconnecting switch parts.

20 A further object of the invention resides in the provision of novel operating means for a switching device, which is so arranged as to enable the device to be constructed for operation at line potential above ground potential, and which is controlled through a non-metallic channel at the will of the operator, thus making it unnecessary to resort to the more expensive structures in which the devices must be insulated for line to ground potential.

25 A further object of the invention is to provide a novel mounting and operating means for a unitary switching device embodying circuit breaker and disconnecting switch features.

30 It is also an object of this invention to provide novel control means for a switching device, wherein in the control station is connected through a non-metallic channel to the operating mechanism associated with the device, thereby safeguarding the operator from possible injury.

35 Still another object is to provide an operating mechanism for a circuit breaker, in which the mass of the moving parts is relatively small and are adapted to be actuated by a high speed, light weight power means, such, for example, as a motor which may be energized from a low voltage source of supply at the device.

40 In accordance with the general features of the invention, it is proposed to provide a unitary switching device of such construction that it may

5 embody both circuit breaker and disconnecting switch features. The actuating mechanism for the circuit breaker feature is of such construction that it may be mounted in the device and the entire device suspended from cables by means of which the device may be raised and lowered into remote and juxtaposed positions relative to the transmission lines. Circuit breaker terminals are provided in the form of disconnecting members which are adapted to resiliently engage the transmission line when the device is raised to a position contiguous the transmission line. By lowering the device, the disconnecting switch parts operate to isolate the circuit breaker.

10 As an additional feature of the invention, the unitary switching device also contains control relays, a source of power for the motor actuated operating mechanism, and a plurality of photo-electric cells which are in circuit with the control relays of the device. The photo-electric cells are so arranged that they may be selectively excited by selective sources of light to open and close the circuit breaker parts of the switching device, whereby the operator is insulated from the switching device by a non-metallic channel.

15 Other objects and features of this invention will more fully appear from the following detailed description taken in connection with the accompanying drawings which illustrate a single embodiment thereof, and in which

20 Figure 1 is a view in elevation showing switching devices embodying the features of the present invention mounted in operative position on a pole or tower of a transmission line;

view of the same, certain parts being shown in full, taken substantially on line VIII—VIII of Figure 7; and

Figure 9 is a view schematically showing the operating mechanism for the circuit breaker and also showing the electrical connections for the various instrumentalities which comprise the control equipment.

As shown on the drawings:

10 In the illustrated embodiment of the present invention, there is shown in Figure 1 a plurality of unitary switching devices, A, B, and C, which are cooperatively associated with the conductors of a transmission line and are suspended from 15 an arm, generally indicated at 10, of a transmission line tower or pole 11.

In the embodiment shown in Figures 1 and 2, each of the switching devices embodies the features of a double break circuit breaker and dis- 20 connecting switch elements, although the features of the invention are with equal facility adaptable to a switching device having single break circuit breaker features. Each of the switching units broadly includes a centrally dis- 25 posed housing 12 for the operating mechanism of the circuit breaker parts. At each end of this housing, there is secured an insulator 13 upon which is mounted a bell-shaped hood or casing 14 which encloses the circuit breaker contact ele- 30 ments. In this instance, the hood 14 also forms an expansion chamber for the circuit breaker fluid. This chamber is extended in the form of a tubular member 15 which is closed at its upper end and also forms a bracket having outwardly 35 extending spaced lugs 16 and 17. The lugs 16 and 17 serve as a guide for a reciprocably mounted rod 18 which is provided at its upper end with a Y-shaped contact member 19 which is adapted to engage the conductors 20 and 20', 40 which cooperate to form one element of the transmission line. These conductors are respectively dead-ended to the cross arm structure 10 through appropriate line type insulators 21—21.

Secured to the rod 18 between the lugs 16—17 45 is a stop or abutment member 22 which functions to abut the lug 16 and limit the upward movement of the rod 18 under the influence of a compression spring 23 having one end bearing against the member 22 and its other end bearing against the lug 17.

The central housing 12 is provided with lifting lugs 24 and 25 at its respective ends. Each of the unitary switching units is supported from the cross arm structure 10 by cables 26 and 27 55 which are connected to the lugs 24 and 25, respectively, through appropriate insulators 28 and 29. The cables 26 and 27 of each switching unit are respectively trained around and anchored to winding drums 28 and 29 which are secured 60 to and rotatable with a shaft 30 having its respective ends pinioned in structural members 31 and 32 of the cross arm structure.

The shaft 30 of the outermost switching unit carries a coiling drum 33 and the shafts 30 of the innermost switching units are provided with similar coiling drums 34 and 34', respectively. All the switching units may be raised and lowered simultaneously by means of an operating cable 35 which is trained over a suitable guide pulley 36 and has one end secured to a manually or otherwise operable winding drum 36 which is located near the base of the transmission pole or tower. The other end of the cable 35 is branched as at a point 36' to form 75 three parts 35', 35'', and 35''', which are re-

spectively connected to the winding drums 33, 34, and 34'. It will, therefore, be obvious that by operating the drum 36, the switching units may be raised and lowered relative to the conductors of the transmission line. Moreover, when the units are in raised position, the disconnecting devices resiliently engage the transmission line conductors, and when the switching devices are lowered, the disconnecting devices operate to automatically disconnect and isolate the circuit breaker from the transmission line.

Referring to Figures 3 and 4, the details of the operating mechanism for the circuit breaker elements are shown. The disclosed operating mechanism may be adapted for use with a variety of 15 different types of circuit breaker, although it is preferred to use the operating mechanism with a circuit breaker such as described in my co-pending application Serial No. 753,085, filed Nov. 15, 1934. The circuit breaker described in that 20 application is of the type wherein the contacts are opened in an arc extinguishing fluid, such as oil or vapor. Broadly, the circuit breaker comprises stationary contact elements which are so disposed as to cooperate with a movable contact 25 element carried by a reciprocable contact rod. On the drawings, this rod is shown as comprising a metallic section 37 and an extension 38 of insulating material, such as horn fibre. These sections are assembled with a contact member 39 30 disposed between their contiguous ends.

In the double break arrangement, the contact rods of both circuit breaker units are operated simultaneously. The contact rod 37 is mounted for reciprocable movement and is provided at 35 one end with an abutment member 40 which seats in a dash-pot cup 41 supported on a bracket 42 secured to the housing 12. This end of the contact rod carries a coiled spring 43 having one end bearing against the abutment member 40 40 and its other end bearing against a guide member 44 which is in sliding relation with the rod and is fixedly secured to an endless rack 45. This rack is provided with parallel side portions and curved end portions having inwardly extending 45 teeth 46 which cooperate with the teeth 47 on a driving pinion 48.

The rack is supported on a plate member 49, as shown in Figure 5, and is provided with an inner guide plate 50 and an outer guide plate 51 50 which overlie the side of the pinion 48 so as to form guiding means for the pinion. The racks are further disposed for longitudinal movement between upper and lower rails 52 and 53 having their ends supported on housing end plates 54 55 and 55 respectively. These rails support a plurality of pivotally mounted rollers 56 which engage the upper and lower surfaces of the rack during its longitudinal movement.

The pinion 48 is secured to a driving shaft 57 60 which in the case of the one rack is connected to a beveled gear 58 and in the case of the other rack, to a beveled gear 59. The beveled gears 58 and 59 are driven from a common beveled pinion 60 which is connected to the driving shaft of a 65 low voltage series motor 61. The motor 61 is pinioned for vertical swinging movement in a pair of spaced brackets 62 and 63, and the driving shaft of this motor, together with the drive shaft 57 upon which the rack pinions are 70 mounted, are all supported as a unit to enable tilting of the driving mechanism as the pinions follow around the rack teeth. In this arrangement, the racks will be moved in opposite directions at the same time.

- Limit switches 84 and 85 are supported on the lowermost guide rail of one of the racks, each of the switches being provided with an actuating arm 86 which is arranged to be engaged by pins 67 disposed at the respective ends of the rack when it reaches its limit of travel. These limit switches are used in connection with the controls for the operating mechanism, as will be explained later in the description.
- 10 As shown in Figures 7 and 8, a tripping mechanism is provided for tripping the circuit breaker so that it will open under abnormal conditions under the influence of the spring 43. For this purpose, the casting 44 is provided with a pair of 15 diametrically opposed radially extending slots 68 and 69, within which there is disposed a latching mechanism for latching the casting 44 and its associated rack to the associated contact rod 37. The rod 37 is provided with a circumferentially 20 extending groove 70 which is adapted to receive a roller 71 which is mounted on a pivot 72 at the free ends of a pair of parallel arms 73 and 74 which are mounted for unitary swinging movement within the slot 68 about a pivot 75. Rotational movement on the arm 73 is effected by 25 means of a toggle joint arrangement composed of a pair of triangularly shaped plates 76 and 77 which are supported for pivotal movement upon a pivot pin 78 at one corner.
- 30 The plates 76 and 77 are pivotally connected by a pivot pin 79 to one end of a link formed by parallel disposed members 80 and 81 which are pivotally connected at their other end to the pivot pin 72. Between the other corresponding 35 corners of the triangular plates 76 and 77, there is pivotally mounted a roller 82. A stop pin 83 is provided for intercepting the counter-clockwise movements of the plates 76 and 77 under the influence of a leaf spring 84 which is looped around 40 the stop pin 83 having one end engaging the pivot pin 78 and its other end engaging the pivot pin 79. When the plates 76 and 77 are against the stop pin 83, the toggle is in such position that the roller 71 is disposed in the groove 70 of the 45 rod 37, whereby the bearing casting 44 is interlocked with the rod 37. It will also be evident that if the plates 76 and 77 are rotated about the pivot pin 78 in a clockwise direction, against the pressure of spring 84, the arms 73 and 74 50 will be rotated in a counter-clockwise direction about the pivot pin 75 to raise the roller 71 out of the groove 70 to thereby release the shaft 37 for a purpose which will be later explained.
- For automatically releasing the locking mechanism just described above, a trip coil 85 is provided for actuating a solenoid plunger 86, when the coil is energized. The solenoid plunger 86 is pivotally connected by a pivot pin 87 to one side of a rocker arm 88 which is pivoted on a pair 55 of spaced brackets 89 and 90 by means of a pivot pin 91. The opposite side of the rocker arm 88 from that to which the solenoid plunger 86 is connected is formed into a pair of spaced arms 92 and 93 which have their ends diametrically 60 disposed on each side of the shaft 37 in such position as to engage the diametrically opposed rollers 82-82 of the latching mechanism and actuate the latch when the tripping coil 85 is energized.
- 65 Referring to Figure 3, it will be noted that a latching mechanism and trip coil is provided for the contact rod 37 of each of the breakers, since the contacts of the breakers are in series to form a double break arrangement. The electrical circuit 70 between the contact rods 37 of the two

circuit breaker mechanisms, when the circuit breaker contacts are closed, would be from the contact rod 37 of one breaker to spring contacts 94 which are supported on end plate 55 so as to frictionally engage the contact rod, through the 5 operating mechanism housing 12 to similarly arranged spring contacts 95 mounted on end plate 54 and thence to the contact rod 37 of the other circuit breaker.

Referring to Figure 4, it will be noted that the 10 housing 12 is provided with an auxiliary compartment which is defined by a box-like structure 96 which extends below the housing 12 and is adapted to receive therein a rectifier 97 and a storage battery 98, which may, if desired, be separated by a partition 99. Supported from the 15 respective ends of the box-like structure 96 and disposed therebelow are hooded sockets 100 and 101 which are adapted to receive photo-electric cells 102 and 103, as shown in Figure 9. The 20 use of the devices just described will be more readily understood from a description of the operation of the control means for the circuit breaker operating mechanism, which is diagrammatically shown in Figure 9.

The photo-electric cells are excited and rendered active to pass current by a light source arranged to project a beam of light from a projector 104 mounted on the transmission line tower or pole, as shown in Figure 1. Referring to Figure 9, the operation is as follows:

The remote control station includes selectively energizable light sources as incandescent lamps 105 and 106. When it is desired to energize lamp 105, a switch 107 is closed which connects the 35 lamp to a source of electrical energy 108 through the following circuit: From one side of the electrical source through switch 107, conductor 109, the lamp 105 and back to the other side of the electrical source through conductor 110. The 40 source of light 106 is controlled in a similar manner through switch 111, which completes a circuit from one side of the electrical source through the conductor 112, the lamp 106 and back to the other side of the electrical source through conductor 110, which is common to both lamps.

For closing the circuit breaker under normal conditions, lamp 105 is energized, which projects a beam of light onto photo-electric cell 102. Excitation of this cell energizes the operating coil 50 of a relay 113, through the following circuit: From one side of a local battery 114, or other source of current through conductor 115, the operating coil of the relay, through conductor 116, through the photo-electric cell 102 and thence back to 55 the other side of the battery 114 by a conductor 117. As soon as relay 113 picks up, it closes its upper contacts 118 which energizes the operating coil of a relay 119 through the following circuit: From one terminal of the battery 98 through conductor 120, conductor 121, conductor 122, contacts 118, conductor 123, the operating coil of relay 119, conductor 124, through the lower contacts 125 of relay 126, and thence through conductor 127 to the other terminal of the battery 60 65 98.

As soon as relay 119 picks up, it closes its contact 128 to energize the motor 81 through the following circuit: From one side of battery 98, through conductor 120, conductor 129, through 70 contacts 130 of the limit switch 65, through conductor 131, the contacts of relay 119, conductor 132, conductor 133 to one terminal of motor 81, and the other terminal of the motor through conductor 134, conductor 135, and thence through 75

conductor 127 to the other terminal of the battery 98. The motor 61 being energized operates through beveled gears 60, 58, and 59 to drive the pinions 48-48 which move the racks 45-45 in opposite directions to close the breaker. Since each rack is latched through the latching member 74 to its associated contact rod 37, the rod 37 is moved so that the contact 39 thereon will interconnect the stationary contact 136 with the 5 spring contact 94, whereby one side of the transmission line 20 is connected to the end plate 55, and the other element of the transmission line 20' is interconnected through a stationary contact 137 and the spring contact 95 to end plate 54. 10 It will thus be seen that, since the end plate 54 and the end plate 55 form a part of the mechanism housing, the conductors 20 and 20' are electrically connected to establish a circuit there-through.

15 20 If it is now desired to open the circuit breaker, the switch 107 being open, switch 111 is closed to energize the light source 106 which in turn excites the photo-electric cell 103. The photo-electric cell 103 being excited by the light rays 25 from the light source 106, the relay 126 is energized through the following circuit: From one side of a local battery 138, or other local source of power, through conductor 139, the operating coil of relay 126, through conductor 140, through 30 the photo-electric cell 103, and thence through conductor 141 to the other side of the battery 138.

35 The operating coil of relay 126 being energized, the relay picks up to close its upper contact 142 and open its lower contact 145. The closing of contact 142 energizes a relay 143 through the following circuit: From one side of the battery 98, through conductor 120, conductor 121, the lower contact 144 of relay 143, conductor 145, through the operating coil of relay 143, through 40 conductor 146, the upper contact of relay 126, through conductors 147 and 127 back to the battery 98.

45 Energization of relay 143 causes it to close its lower contact 148 to energize the motor 61 through the following circuit: From one side of the battery 98, through conductor 120, conductor 149, conductor 150, contact 148, conductor 131, through contact 151 at limit switch 64, and thence through conductors 152 and 133 to one terminal 50 of the motor 61 and to the other terminal of the motor through conductor 134, conductor 135 and thence through conductor 127 to the other side of the battery 98.

55 Simultaneously with the closing of the lower contact 148 of relay 143, the upper contact 163 thereof is also closed to trip the circuit breakers so that they may rapidly open under the influence of springs 43-43. The trip coils 85-85 in this case are energized through the following circuit: 60 From one side of the battery 98 through conductor 120, conductor 149, contacts 163 of relay 143, conductor 164, one trip coil 85, conductor 159, the other trip coil 85, conductor 160, conductor 135, and thence through conductor 127 to the other 65 side of the battery.

65 Since the latching members 74 are disposed under the respective trip coils, when the breakers are closed, the energization of the trip coils will unlatch the rods 37 relative to the bearing castings 44, whereupon the compression springs 43 operate to move the contact rods to circuit open position.

70 75 The circuit breakers now being open and the motor 61 running, the motor operates to rotate the pinions 48-48 to move the respective racks

45-45 in the opposite direction to bring them to their normal positions with the circuit breakers open. As a result of this movement of the racks, the latching members 74 will again latch the racking mechanism and the rods 37 together and 5 will also recompress the springs 43 so that the compressed springs, racks and contact rods will again be moved as a unit in closing the circuit breaker.

The operation will now be considered under abnormal conditions; for example, the opening of the circuit breakers upon an overload. When the circuit breakers are closed, it will be observed that transmission line current will flow from contacts 136-137 through the respective contact rods 15 37-37 to the contact springs 94 and 95 which are in engagement with the contact rods 37. Moreover, each of the contact rods 37, when the breakers are closed, is surrounded by a current transformer 153. One of the current transformers 153 is connected through conductors 154 and 155 to the operating coil of an overload relay 156. This relay, upon being energized by the current transformer during overload condition, closes its contacts 157, whereby the tripping coils 85-85 25 are energized through the following circuit: From one side of the battery 98 through conductor 120, conductor 149, conductor 150, contacts 157 of relay 156, conductor 158, trip coil 85, conductor 159, the other trip coil 85, and thence through 30 conductor 160, conductor 135 and conductor 127 to the other side of the battery. The operation of the trip coils in opening the circuit breakers is the same as already described above.

The other current transformer 153 is connected through conductors 161 and 162 to one set of terminals of the rectifier 97. The other set of terminals are, of course, connected to the storage battery, so that the battery will be charged from the transmission line.

40 It will be observed that the contacts of the limit switches 64 and 65 also function to bridge the contacts 128 and 148 of relays 119 and 163 during the initial closing and opening operations. The switches 107 and 111 need therefore be 45 closed only a short time and may be immediately opened after the closing and opening operation has begun.

In the control arrangement described above, the photo-electric cells 102 and 103 will, when 50 simultaneously excited by sunlight or other light source than the sources 104 and 105, operate to simultaneously energize relays 113 and 126. However, the circuit breaker mechanism will not be operated, since the contacts of these 55 relays are interlocked through each other.

55 From the foregoing description, it will be apparent that the herein described invention provides operating means for a circuit breaker which permits its embodiment in a unitary 60 switching device having both circuit breaker features and disconnecting switch features, which embodies novel control equipment which, together with the foregoing feature, enables an economical installation in outdoor stations, and in which the control station for the circuit breaker is connected to a non-metallic channel, thus protecting the operator against possible injury.

65 In the description and claims defining the present invention, the terms "circuit breaker" and "disconnecting switch" are used in the following sense:

70 75 *Circuit breaker*.—A device constructed primarily for the interruption of a circuit under 75

infrequent abnormal conditions; for example, an overload.

Disconnecting switch.—A device ordinarily used for sectionalizing bus bars or circuits, or 5 for isolating apparatus for grounding or repair, but not for switching under load.

Now, it is of course to be understood that although I have described in detail a preferred embodiment of my invention, the invention is 10 not to be thus limited but only insofar as defined by the scope and spirit of the appended claims.

I claim as my invention:

1. The combination with an overhead transmission line including a pair of dead-ended conductors, of switching means comprising a metal housing, a circuit breaker within said housing, manually controlled means within said housing for actuating said circuit breaker to open and to closed position, contact members for said circuit breaker carried by said housing, flexible means for suspending said housing free of the ground with said contact members in engagement with the respective conductors, and insulators between said flexible means and said housing, whereby said metallic housing may assume a potential differing from that of the ground.

2. The combination comprising an overhead transmission line including a pair of dead-ended conductors, a circuit breaker having circuit-controlling contacts between terminals adapted for engagement with said conductors, a metal casing housing said circuit breaker, and suspension means to raise and lower the casing to establish 35 and disestablish an electrical circuit between said terminals and conductors.

3. In combination, an elevated transmission line, a circuit breaker and means suspending the same contiguous said line and in electrical circuit therewith, power means independent of said line and carried by said breaker for opening and closing the same, and means to control the operation of said power means, said control means being remotely located and out of electrical connection with said power means.

4. In combination, a suspended transmission line, a circuit breaker suspended above ground contiguous said line and in electrical circuit therewith, power means independent of said line and carried by said breaker for opening and closing the same, means to control the operation of said power means, said control means having electrically energizable parts local to the power means, and electrically energizable parts remote thereto, and a non-metallic channel for interconnecting the local and remotely located parts.

5. In combination with a switching device having contacts operable to open and close an electrical circuit, a metal housing for said switching device, means insulating said housing from ground, power means independent of said electrical circuit for operating said contacts, control means for said power means including a remotely located station, and a connection to said station including a non-metallic channel.

6. In combination with a switching device having contacts adapted to open and close an electrical circuit, a metal housing for said switching device, means insulating said housing from ground, power means independent of said elec-

trical circuit for operating said contacts, electrically energizable means including a photo-electric cell for controlling the power means, and remotely located light-producing means operable to vary the operating characteristics of the photo-electric cell. 5

7. In combination with a switching device having contacts adapted to open and close an electrical circuit, a metal housing for said switching device, means insulating said housing from ground, power means independent of said electrical circuit for actuating said contacts, control means for said power means including a device having characteristics responsive to light rays, and a remotely located source of light for controlling the characteristics of said device. 10 15

8. Operating means for a circuit breaker having a pair of contacts movable into and out of engagement to open and close an electrical circuit, means operative in one direction to close the contacts and in another direction to open the contacts under normal conditions in said circuit, a spring under compression during normal closing of the breaker, and means energizable to release said spring to open the contacts under abnormal conditions in said circuit, said first means being operative, when moved in a direction to normally open the contacts, to compress said spring after it has functioned to open the contacts under abnormal conditions. 20 25 30

9. Operating means for a circuit breaker having contacts adapted to be opened and closed to control an electric circuit, said means comprising an automatically reversing elongated rack, a member for latchingly connecting the rack to one of said contacts, whereby movement of the rack in one direction will close the contacts, motor means for moving said rack in opposite directions to effect the normal opening and closing of the contacts, a compression spring operative 40 independently of said rack and motor means to open said contacts upon releasing said member, and means responsive to an abnormal condition in the electrical circuit for releasing said member when the contacts are closed, the subsequent 45 movement of the rack in the contact opening direction operating to recompress the spring and latchingly connect the rack and contacts after the spring has functioned to open the contacts. 50

10. In a power transmission system, the combination with an overhead transmission line including a pair of dead-ended conductors, supporting means, and insulators suspending the adjacent ends of said conductors upon said supporting means, of a unitary switching device comprising a metallic housing, terminal contact members carried by and insulated from said housing, a circuit breaker within said housing for completing a circuit between said contact means, means suspending said housing upon said supporting means, said suspending means including insulators at said housing and cables extending from said insulators to the supporting means, and means operable from the ground for actuating said cables to raise said housing to engage said 60 contact members with said conductors and to lower said housing to separate said contact members from said conductors. 65 70
